Primary Examiner — Vy N Koenig(74) Attorney, Agent, or Firm — Lewis Roca Rothgerber Christie LLP(57) CLAIM

The ornamental design for a folding step stool, as shown and described.

DESCRIPTION

FIG. 1 is a perspective view of a folding step stool design; FIG. 2 is a top view thereof;

FIG. 3 is a left side view, which is a mirror image of the right side view thereof;

FIG. 4 is a bottom view thereof;

FIG. 5 is a front view thereof; and,

FIG. 6 is a rear view thereof.

The broken lines shown represent unclaimed subject matter and form no part of the claimed design.

1 Claim, 5 Drawing Sheets(56)
